Application April 23, 1938, Serial No. 203,783
In Belgium April 27, 1937

5 Claims. (Cl. 120—114)

The present invention relates to pens of all kinds and especially, although not exclusively, those employed by industrial and advertisement draughtsmen for tracing letters or ornaments 5 made of simple or multiple-parallel lines and also for forming by pressure of the pen nib on the paper all kinds of signs or ornaments.

In order to obtain this result, which calls for an important flow of ink, continuous and without 10 the necessity of frequent refilling, two chief difficulties are to be overcome, to wit:

1. That inherent in the fact that the pen should be able of maintaining a substantial reserve of liquid (ink or paint) exerting only a negligible pressure on the part in contact with paper (too high a pressure would produce an accumulation of ink and stains).

2. That due to the adjustment of the ink flow, which is to be proportional to the thickness of 20 the line to be traced.

The object of the present invention is to provide a pen which avoids these difficulties.

According to the present invention, these difficulties are eliminated in the following manner:

a. I constitute on the pen a reserve of liquid in the form of a sheet which is horizontal or little inclined in the direction of the nib of the pen, said sheet being of small depth and large 30 area, and being located as close as possible to the plane of marking, so as to reduce to a minimum the height of the reserve above said plane, said height being practically of a value ranging from one to some millimeters, according to the 35 thickness of the line to be traced.

b. In opposition to what takes place in ordinary pens, in which the flow of ink is obtained, when desired by the operator, by the movement of two branches normally juxtaposed, away from 40 each other, this movement producing a flow of liquid due to the action of capillarity and especially of gravity, due to the considerable inclination of the pen, one of the improvements according to the present invention consists in 45 producing the flow of the reserve of liquid of the pen under the effect of the suction of the liquid already spread on the surface of paper, in such manner that the flow of liquid thus obtained is due nearly wholly to the action of capillarity 50 and gravity has but a negligible effect in consequence of the low height of the reserve as above mentioned. In this way, the flow is proportional to the area of liquid spread by the tracing end, and it is stopped when the stream is cut off, that 55 is to say when the pen is lifted.

c. Ink is conveyed to the under surface of the marking pad through a hole or (in the case of a pen of large size) several holes, provided through the tracing end so as to connect the under face thereof with said reserve. These 5 holes are perpendicular to the surface to be marked and their diameter is proportional to the viscosity of the liquid that is employed and to the thickness of the line to be traced (without however reaching a size such than capillary 10 phenomenons are eliminated).

d. I create a film of liquid connecting the reservoir of the pen to the outflow orifices of the tracing part, by placing above the latter a screen of a direction substantially at right angles to the axes of the holes. This screen, which is nearly in contact with the orifices, forms with the bottom of the cavity which contains the reserve of liquid, a very sharp dihedral angle the apex of which coincides with the end of the tracing part. 15

This screen establishes the necessary connection between the reserve and the tracing end of the pen, producing, by capillarity, the flow of ink from said reserve toward the orifices of the holes of the tracing end; on the other hand, it prevents an exaggerate rate of flow, especially in the case of pens of big size, the holes of which are very large. In this way, the necessary flow of ink is obtained chiefly by capillary action 20 rather than gravity.

e. The capillary connection between the sheet of liquid that is spread and the reserve of ink in the pen is facilitated by adapting to the viscosity of the liquid and also to the nature and state of polishing of the surface on which the tracing 25 is to take place the surface of the tracing part that is in contact therewith. In the case of viscous liquids, a rough marking surface or a surface provided with small radial grooves around the holes, or again a surface covered with skin or a net of suitable mesh size, prevents the marking surface from scraping on the surface of paper, thus eliminating any capillary connection, and it permits liquid to flow freely and without excess onto the tracing plane.

f. Finally, in order to facilitate cleaning after the pen has been used and to ensure the good 30 operation and preservation of the pen, the screen above mentioned is made removable.

In order to clarify the description and to avoid any misunderstanding, the parts that constitute the pen are defined as follows:

The "marking pad" is the end of the pen in contact with the tracing plane.

The "pen body" is the substantially horizontal part containing the reserve of ink.

The "screen" is the element, preferably in the form of a curved blade, which controls the flow of ink toward the tracing part.

The "shaft" is the semi-cylindrical part of the pen that is inserted into the pen-holder.

Preferred embodiments of the present invention will be hereinafter described with reference to the accompanying drawings, giving merely by way of example, and in which:

Figs. 1a, 1b, 1c and 1d are a vertical sectional view, a part bottom view, a top plan view and edge view respectively, of a first embodiment of the invention;

Figs. 2a, 2b and 2c are similar views, respectively, corresponding to another embodiment;

Figs. 3a, 3b and 3c are a longitudinal vertical section, a plan view and a horizontal section on the line 3c—3c, respectively, of still another embodiment;

Figs. 4a and 4b are a longitudinal vertical section and a plan view, respectively, of still another embodiment;

Fig. 4c is a detail view showing separately the screens of the pen of Figs. 4a and 4b;

Figs. 5a and 5b are a longitudinal vertical section and a plan view, respectively, of still another embodiment;

Figs. 6a and 6b are a longitudinal vertical section and a plan view, respectively, of still another embodiment;

Figs. 7a and 7b are a longitudinal vertical section and a plan view, respectively, of still another embodiment;

Figs. 8a and 8b are a longitudinal vertical section and a plan view, respectively, of still another embodiment;

Fig. 8c is a corresponding view of the end of the end of the pen, the screen and the tracing part being removed;

Fig. 9 is a plan view of still another embodiment;

Fig. 10 is a section on the line 10—10 of Fig. 9 and Fig. 11 is a section on the line 11—11 of Fig. 10;

Fig. 12 is a plan view of a big size pen made according to the present invention;

Fig. 13 is a sectional view on the line 13—13 of Fig. 12;

Figs. 14 and 15 are corresponding longitudinal vertical sections;

Fig. 16 is a bottom view corresponding to the last mentioned embodiment;

Fig. 17a is a plan view of another embodiment;

Fig. 17b is a partial side view;

Figs. 17c and 17d are a corresponding axial section and plan view, respectively.

Figs. 1a, 1b and 1c on the one hand, and 2a, 2b and 2c on the other hand, show, on an enlarged scale, the essential elements of the pen according to the present invention, that is to say the pen body 1, carrying the marking pad 2, and the screen 3 fitted above said body. Figs. 1a, 1b and 1c relate to the case of a pen tracing lines by rubbing of its end upon the surface of paper. Figs. 2a, 2b and 2c relate to the case of a pen tracing the desired figure by pressure of the point. In both cases, the marking pad is in the form of a cylindrical or prismatic body of very low height, of vertical axis, the lateral wall of which is prolonged on one side by the body of the pen. The base of this body is in the form of any plane geometrical figure, or of any other figure made of straight or curved elements the

whole of which reproduces a sign or a symbol. This body is provided with vertical holes 4 extending throughout it, the number and section of said holes being in proportion with the area of the base and the viscosity of the inking liquid. 5 Small grooves 5 of suitable size, sufficiently small for avoiding any possibility of modifying the pattern reproduced by the marking pad, are provided in the under surface thereof, radiating from the orifices of the above mentioned holes 10 so as to facilitate the flow of the liquid along the tracing paper or other surface and to avoid any scraping action.

The marking pad thus described can be obtained by cutting from a metal sheet, by stamping of an eyelet, or again by winding of a metallic sheet or wire so as to form a cylinder having a vertical axis and the base of which is of any shape.

The body of the pen is constituted by a plate 1 of large area, extending to the rear of the marking pad 2, in such manner that the plane of the pen body is substantially horizontal and is at a distance from the lower outflow orifice 4 of the marking pad which ranges from 1 to 3 millimeters according to the size of the pen.

The screen 3 is made, in its essential part, where it is in contact with the inking liquid, of a flexible blade cut into a shape such that it covers exactly the body of the pen and the marking pad thereof. This screen forms, together with these elements a very sharp dihedral angle the apex of which coincides with the upper orifice or orifices of the tracing part. Owing to its movable connection with the remainder of the body, this screen can cover the body of the pen or it can be moved apart therefrom so as to permit cleaning.

All the embodiments which will now be described, whatever be the connection of the shaft 40 with the body or with the screen present the same characteristic features as above stated.

As for the means for connecting the shaft with the pen body, they may be made in various manners, for instance as shown by Figs. 5a, 5b, 6a, 6b, 45 7a, and 7b.

Figs. 5a and 5b show a connecting arrangement constituted by a stamped part 1 connecting with the necessary rigidity the rear of the body and the shaft 24. The flexible screen 3 is fixed 50 to the pen-holder and it may be superposed to the pen body by a ring slidable parallelly to the shaft and which applies said flexible screen against it.

In the embodiment of Figs. 6a and 6b, the 55 connection between the body 1 and the shaft 24 is devised in such manner as to give a certain elasticity to the pen body, the end of which forms two parallel elements 7 and 8, the latter being capable to trace lines either together or separately according to the manner in which the pen is held by the operator. In this case, screens 3 and 3' cover their respective pen bodies 7 and 8, or can be moved aside, by lateral pivoting about pins 6 riveted to said bodies.

Figs. 7a and 7b show the connection of body 1 with shaft 24 arranged in such manner as to permit of turning the pen body in any direction whatever. For this purpose, the pen body carries, near the marking pad, a bridge 22 on 70 which a threaded rod 25 is fixed. The shaft 24, bent at 27, is provided with an eye adapted to fit on said rod, and it is fixed thereon by means of a milled nut 23. In this case, the screen 3 is inserted from the rear and fixed on the rear 75

edge 26 of the body by a portion 26 thereof acting as a clip.

However, although the embodiments above described permit of obtaining satisfactory results, I have found that it is particularly advantageous to utilize an arrangement in which the horizontal pen body 1 is connected to the shaft 24 through two branches 28 which extend laterally from said shaft.

Figs. 3a, 3b and 3c show an embodiment of this kind. The two branches 28 are connected to the body 1 at their ends, near the marking pad 2, the angle they make therewith being approximately 50°. At the rear, at 26, the body is slightly bent upwardly, so as to prevent this end of the pen from rubbing on paper when writing. Between the branches 28, the shaft carries two lugs 29 and 30, cut and shaped so as to form a support for screen 3.

The screen such as above described is prolonged toward the front by a narrow portion 9, constituting an operating finger, curved into a circular arc, at the level of lugs 29-30 so as to form a cylinder 10 of horizontal axis the ends 25 of which fit on two cylindrical projections 11 carried by said lugs 29, 30, as shown by Fig. 3c.

Of course, within the scope of the invention, I may obtain a multiplicity of combinations by juxtaposition of elements above described. For instance, multiple elements may be grouped into a single pen or they may be mounted side by side, with suitable intervals between them. These elements may eventually come into play either simultaneously or separately, by the action of springs or under the effect of their own elasticity under the effect of the pressure exerted by the operator.

By way of example, Figs. 4a, 4b and 4c show one of these combinations. The body of the pen is constituted by two elements 1 and 1' juxtaposed and connected together at the rear, at 26. One of the elementary bodies 1 is fixed and connected to the shaft 24 through two branches 28 as in the embodiment just above described. The other elementary body, 1', is, laterally, in overhanging position with respect to the first body and its marking pad 2 projects downwardly with respect to the marking pad 2' of the fixed body. In view of the elasticity of the metal that is employed, when the pressure exerted by the operator varies, only one, or both, of the marking pads can come into contact with the paper surface, for tracing either one line or two juxtaposed lines. Each body is fitted with its respective screen, 3 or 3', said screens being pivoted about a common horizontal pin 10, carried by two supports 11 carried by the rear part 26 of the pen body.

Only the screen 3 of the fixed body carries an operating finger 9. The other screen 3' is driven by the first screen owing to the provision of a projection 13 extending laterally above the adjacent screen.

Of course, the above described embodiment characterized by a unilateral arrangement of the flexible pen body is given merely by way of example and this element can occupy any other position. It may be of twofold structure, extending on both sides of the fixed body, or it may be housed between two fixed parts or it may be fitted in a notch cut in a fixed part.

Figs. 8a and 8b (the latter being a plan view the lower half of which shows the pen without screen) show an embodiment which permits of interposing a textile net 31 between the tracing

part 2 and the tracing plane 32, especially in order to permit of writing on hard and polished surfaces. The marking pad 2 above described is fixed on the end of the pen body 1 and housed in an aperture 33 provided for this purpose. 5 Owing to the flanges 34 formed on its periphery, the marking pad 2 bears upon the edges 35 of the aperture 33 of the pen body, stretching between itself and the periphery of said aperture, under the pressure of a pin 36, a piece of very thin skin or of a woven fabric 15. Fig. 8c shows the end apertured at 33, the screen and the marking pad 2 being removed. The screen is identical to that of the fixed body of the preceding embodiment. However, in the case of big 10 size pens, it may be provided, as shown by Fig. 8a, with a supplementary reservoir 14 in communication with the lower recess 12 through a hole 13, adjusted by means of a needle screw 14. 15

In Figs. 9 to 11, the hole 4 is considerably 20 larger and I insert therein a simple or multiple pad 16, the matter thereof being soaked with ink or paint and the pad acting, among other things, as a consequence of the fact that it forms a plastic intermediate resting upon the surface 25 which receives the inscriptions.

In the modifications shown by Figs. 12 to 16 inclusive, which are especially advantageous in the case of big size pens and multiple tracing parts, which increase the possibilities of trac- 30 ings obtained with a single pen, I have shown at 17 a fixed rectangular marking pad, containing a second tracing part 18, of cylindrical shape, which projects more or less under the action of spring 19. The liquid inlet holes 20 and 21 35 feed liquid to the corresponding marking pads, respectively. With this arrangement, the operator can at will either trace a line of a width equal to the whole of the marking pad or a line of a width equal to the diameter of cylinder 18. 40

This pen is further provided with a bridge-shaped part 22 permitting, owing to nut 23, a variable orientation of the pen.

Figs. 17a, 17b and 17c show a modification which permits of writing in an oblique or vertical 45 plane.

Fig. 17b shows the frame for fixing the net on the marking pad. In this embodiment of my invention, the pen body 1 and the screen 3 are of the same shape and position as above described. 50 The marking pad is also constituted by a prism having a base of any shape intended to be applied on the paper surface and to cooperate therewith. But this prism is cut in such manner that its lower base 37 is parallel to the surface 55 to be written on and it is laterally connected to the pen body as in the other embodiments.

The ink feed holes 4 provided in the marking pad 2 are directed obliquely and start, as in the other embodiments, close to the apex of the 60 dihedral angle made by screen 3 and body 1. The screen 3 pivots about an axis 6 carried by two lugs 29 provided at the rear and on each side of the pen body. The connection of the body 1 with the shaft 24 is obtained by means of two 65 branches 10 which laterally prolong said shaft and hold the pen body 1 from below on either side and close to the marking pad 2, making an angle of about 60° with the horizontal plane. The interposition of a textile net 15 between the 70 marking pad 2 and the tracing plane 32 is obtained by swinging about axis 12 a frame 11 which covers the marking pad 2 by applying the fabric against it. The frame is kept in position and the fabric is stretched by the action of two 75

springs 14, bearing upon two notches 15' of the tracing part with which this frame is assembled.

Of course, the pen might be made of any suitable material other than a metal, such for instance as a plastic material, wood, glass, and the like.

In a general manner, while I have, in the above description, disclosed what I deem to be practical and efficient embodiments of the present invention, it should be well understood that I do not wish to be limited thereto as there might be changes made in the arrangement, disposition, and form of the parts without departing from the principle of the present invention as comprehended within the scope of the accompanying claims.

What I claim is:

1. A reservoir pen which comprises, in combination, a pen body of general flat shape forming the bottom of the ink reservoir, a screen carried over the bottom, to form the ceiling of the reservoir and making a sharp dihedral angle with the pen body, a shaft for fixation of the pen to a penholder, said shaft being in such angular

25 relation with the pen body that said body be in substantially horizontal position when the penholder is held in the normal angular position for writing, a marking pad at the free end of the pen body, slightly projecting from the under surface 30 thereof, and means for conveying ink by capillarity from the ink reservoir onto the surface to be marked, through the marking pad.

2. A reservoir pen which comprises, in combination, a pen body of general flat shape forming the bottom of the ink reservoir, a screen movably carried over said bottom to form the ceiling of the reservoir and making a sharp dihedral angle with the pen body, a shaft for fixation of the pen to a penholder, said shaft being in such an angular relation with the pen body that said body be in substantially horizontal position when the penholder is held in the normal angular position for writing, a marking pad at the free end of the pen body, projecting from the

under surface thereof so as to hold said surface at a distance ranging approximately from 1 to 4 millimeters from the surface to be marked, and means for conveying ink by capillarity from the ink reservoir onto the surface to be marked, 5 through the marking pad.

3. A reservoir pen which comprises, in combination, a pen body of general flat shape forming the bottom of the ink reservoir, a screen made of a bent metal sheet movably carried over said bottom, forming the ceiling of the reservoir and making a sharp dihedral angle with the pen body, having its apex at the free end of the pen body, a shaft for fixation of the pen to a penholder, said shaft being shaped and bent so 10 that the pen body lies in substantially horizontal position when the penholder is held in its normal tilted position for writing, a marking pad at the end of the pen body, projecting from the under surface thereof to hold said surface at a 15 small distance from the surface to be marked, and means for causing the liquid in the reservoir to flow by capillarity onto the surface to be marked, across the marking pad.

4. A reservoir pen which comprises, in combination, a pen body of general flat shape forming the bottom of the ink reservoir, a ceiling for the reservoir formed of a bent metal sheet movably carried by the bottom, and making a sharp dihedral angle with the pen body, a shaft for 20 fixation of the pen to a penholder in such a manner that the bottom of the ink reservoir lies in a substantially horizontal position when the penholder is held in its normal tilted position for writing, a multiple marking pad at the end of the 30 pen body, said body being elastically deformable so as to permit of applying either one or both marking pads on the surface to be marked.

5. A pen according to claim 4, in which said marking pads are movable vertically with respect 40 to one another, and in which means are adapted to be operated by manual pressure for causing at least one of said pads to project downwardly.

PIERRE CHOUFFET.
